UNITED STATES PATENT OFFICE

ROBERT C. NICHOLSON, OF OROVILLE, CALIFORNIA

DESIGN FOR A WATCHCASE BACK OR ANALOGOUS ARTICLE

Application filed December 2, 1931. Serial No. 41,940. Term of patent 14 years.

To all whom it may concern:

Be it known that I, ROBERT C. NICHOLSON, a subject of Great Britain, residing at Oroville, in the county of Butte, and State of California, have invented a new, original, and ornamental Design for a Watch Case Back or Analogous Article, of which the following is a specification, reference being had to the accompanying drawings, forming part thereof.

Fig. 1 is a plan view of a watch case back, showing my new design; and Fig. 2 is a cross section of the same. The design is a geographical view of a mountainous section of land.

I claim:

The ornamental design for a watch case back or analogous article, as shown and described.

ROBERT C. NICHOLSON.
